HYDRAULIC PRESS

Johann Peter Spengler, Berlin, Germany

Application June 5, 1939, Serial No. 277,525
In Germany October 2, 1935

4 Claims. (Cl. 25—91)

The invention relates to a hydraulic press with a reciprocating filling slide provided upon the press table for filling the moulds and to the operation thereof for the production of shaped bodies from ceramic masses.

It is characteristic of the operation of the hydraulic press according to the invention that the filling slide is employed as the sole control member in that, solely by the motion of the filling slide, pressure water is first supplied to the upper piston and that after a certain pressure has been reached the lower piston is operated by means of an intermediate valve and a piston acting as an accumulator. After removal of the pressure in the upper stamp the pressure water from the accumulator lifts up the lower stamp. This process can however not begin until after a maximum pressing effect has been produced. The pressed body however at first still remains clamped fast between the upper and lower stamps and indeed until the moment where the upper piston is lifted up, whereupon removal of the pressed body then immediately takes place.

The upper piston is preferably a double piston and consists for example of a smaller piston and integral with this the actual pressing piston.

The pressure liquid first acts upon the piston of smaller cross-sectional area, whereupon the pressure liquid, when the double piston has first travelled a certain distance, comes into action upon the surface of the actual pressing piston. As it sinks the pressing piston sucks in filling liquid after it into the pressing cylinder through a feed conduit provided with a suction valve.

In one embodiment of the apparatus, the small piston is provided with a bore and a suction valve is connected to the pressing cylinder for sucking in filling water. Upon downward motion, after a short path has been travelled, a valve is automatically opened in the bore of the smaller piston so that the pressure liquid now passes through the bore of the smaller piston into the pressing cylinder and acts upon the surface of the larger piston, whereby the suction valve of the filling liquid feed conduit is closed. During the actual pressing operation pressure liquid from the upper piston is at the same time stored up and this stored pressure liquid is employed to produce a pressure upon the lower stamp for expulsion. The apparatus is so constructed that the expulsion pressure begins to act already during the main pressing operation, however the expulsion of the shaped body cannot take place until the desired adjustable maximum pressure has been attained. This arrangement ensures that

entirely uniformly pressed shaped bodies are produced with the press.

For this purpose a pressure accumulator for the pressure water from the upper piston is connected between the pressing cylinder and the cylinder of the expulsion piston; this pressure accumulator incorporates a pressure valve which is adjustable according to the desired pressure for the pressing operation and the valve chamber of which is connected with a piston under load. A tube conduit forms the connection with the expulsion piston so that already during the actual pressing operation the expulsion piston is ready for the lifting. Hence only a small accumulator is necessary.

The to and fro motion of the filling slide arranged upon the press table for the press moulds controls the pressing valve and the expulsion valve, and the press stamp is pressed into the press mould and thereby the preliminary pressing, de-aeration, complete pressing and expulsion operations are effected. For this purpose a conduit leads from the pressing valve to the space above the bore of the piston of smaller cross-section which is positively connected to the pressing piston. Moreover a conduit leads to the pressure accumulator incorporating the pressure regulating valve to which the cylinder of the loaded pressure piston is connected, from whence a conduit leads to the expulsion piston and the expulsion valve. The pressure piston is so strongly loaded by means of a spring or the like, that it yields a higher pressure than is necessary for the expulsion of the pressed body.

Earlier hydraulic presses are indeed already known in which the expulsion is also effected automatically with the aid of the filling box. In the earlier press however the filling box is not the sole and not the initiating or control member.

In the earlier apparatus it is a matter of an entirely automatic operation which is initiated by the main pressure valve. With the latter, adaptation to varying circumstances is not possible. According to the invention on the other hand, and having regard to this fact, the hydraulic press is semi-automatically operated.

The construction thereof is quite particularly simple and the press, in spite of its manual operation, has the same performance as a completely automatic hydraulic press. This is achieved because the operator has only a single movement to carry out, consisting of sliding the filling box to and fro, which makes possible a rapidity of operation such as cannot be obtained when operating two control parts.

It is a further advantage of the press according to the invention that the production of a uniform pressing is no longer dependent upon the watchfulness of the operator, because the apparatus is so constructed that expulsion can never take place until after the maximum adjusted pressure has been reached and that the shaped body is clamped fast between the upper and lower stamp until the moment where it can be removed after lifting of the upper piston. Thus any distortion of the pressed piece after the maximum pressure has ceased is avoided, so that also thin-walled ceramic bodies, wall plates, floor plates, can be produced in a wholly plane form and damage to the shaped bodies is prevented.

An embodiment of the invention will now be described by way of illustration with reference to the accompanying drawing, in which

Fig. 1 shows a vertical section taken on the line I—I of Fig. 2 through a hydraulic press according to, and for carrying out the process of, the invention,

Fig. 2 is a section on the line II—II of Fig. 1, and

Fig. 3 is a section on the line III—III of Fig. 2. Referring to the drawing, the filling slide *a* with the drivers *b*, *c* and *b*₁, *c*₁ slides upon the press table in the channeled guide members *d*. The drivers *b*, *c* and *b*₁, *c*₁ control the pressing valve *e* and the expulsion valve *f* as the filling slide *a* slides backwards and forwards. The pressing valve *e* is connected through a tube conduit *g* with a cylinder *j* for the small portion of unitary piston *i*, *l*₁. This cylinder is provided with a bore in which an automatically controlled valve *k* is seated. The bore of piston *i* opens at *i*₁ into the pressing cylinder *l* to which a suction valve *m* is connected. The cylinder *j* is connected through the tube conduit *n* with the pressure-regulating valve *o* which can be regulated by means of the spring *p* or the like. The valve chamber of the pressure valve *o* is connected with the regulable pressure piston *q* in the cylinder *q*₁. The piston is strongly loaded by means of a spring or by lever pressure, so that a higher pressure is exerted than is necessary for the expulsion of the pressed body. The pressure piston *q* is connected through the tube conduit *r* with the expulsion piston *s* and the expulsion valve *f*. The pressure liquid flows in in the direction of the arrow *t*, the exhaust water is led off in the direction of the arrow *u* and the suction valve *m* during the downward motion of the piston *i* sucks the filling liquid into the pressing cylinder *l* in the direction of the arrow *v*.

In Fig. 2 the control by means of the filling slide *a* with the drivers *b*, *c* and *b*₁, *c*₁ is shown as well as the valve arrangement for the pressing valve *e* and the expulsion valve *f*. The valves *e* and *f* are movable upwardly and downwardly and are constructed as screw-threaded pins. They are arranged to be under the pressure of springs *h*₁, *h*₂ as shown in Fig. 3 and have at the upper end a head *t*₁, upon which the drivers *b* and *c* act and produce alterations in position.

The drivers *c* and *c*₁ are in the form of wedges of hard rubber or some other resilient material, and engage frictionally with the valve heads *t*₁ which are milled, corrugated or roughened at their periphery. Moreover an annular member carrying a lug is rigidly mounted upon the valve spindles *e* and *f*. A tension spring *h* engages with each of these lugs and is secured at its other

end to a rigid part of the housing of the valves *e* or *f*.

Upon pushing the filling box forward the driver *c* rotates the head *t*₁ and thus moves the valve spindle *e* into the closed position. At the same time the spring *h* is tensioned. When the filling box *a* is withdrawn the driver *c* moves out of engagement with the valve head *t*₁ and the spring *h* rotates the valve spindle *e* back into the starting position.

Instead of frictional drive with a tension spring, a lever control, eccentric drive, cam control or the like connected to the filling box *a* may be employed for operation of the spindles *e* and *f*.

The manner of operation of the hydraulic press is as follows:

The filling slide *a* is pushed forward in the guides *d* for filling the pressing mould and when filling has been accomplished is withdrawn beyond the zero position. During the latter operation the driver *b*, *c* closes the pressing valve *e*. The pressure water flowing in at *t* can no longer flow away unhindered in the direction of the arrow *u* but enters through the tube conduit *g* into the cylinder *j* of the small piston *i* of unitary piston *i*—*l*₁ and presses it—the valve *k* being closed—downwardly until the valve is opened by the striking of member *w* at the end of the valve guide rod. Opening of the valve *k* takes place when the upper press stamp *l*₁ has already penetrated into the pressing mould and the compression of the material to be pressed takes place, that is when the lost motion has been overcome. The pressing piston *l*₁ has necessarily accompanied the piston *i* in its accelerated motion and has thus sucked in filling water through the suction valve *m* into the pressing cylinder *l*. The pressure liquid now flows through the opened valve *k* into the pressing cylinder *l* through port *i*₁, closes the suction valve *m* and presses the pressing piston *l*₁ with its upper pressing piston *i* into the pressing mould. By means of the periodic motion of the filling slide the preliminary pressing, de-aeration and main pressing operations and also the expulsion are effected. The pressure valve *o* does not open automatically until the prescribed maximum pressure has been reached; this valve can be regulated according to the pressing pressure and stores up the pressure liquid necessary for the expulsion in the cylinder of the pressure piston *q*. The pressure piston *q* is directly connected through the tube conduit *r* with the expulsion piston *s*. In this position the press is under high pressure but the expulsion pressure soon works itself out. By means of a small forward movement of the filling slide *a*, the pressing valve *e* is opened, the entry of pressure liquid *t* is interrupted and the liquid flows out in the direction of the arrow *u* and the pressure process in the pressing cylinder *l* is finished. At the same moment the pressure liquid collected at *q* closes the valve *o* and, through the tube conduit *r*, presses the expulsion piston *s* upward and lifts the pressed body from out of the pressing shape. The pressed body remains shut in between the upper and lower stamp plates during the expulsion until it has been lifted completely out of the mould. A mechanical or hydraulic piston returning means of desired construction then withdraws the large pressing piston *l*₁ with the piston *i* into its original position. One such means is shown in Figure 1. It comprises springs *x* and *x*₁ and plate *y*. Springs *x* and *x*₁ extend between a portion of the housing

defining cylinder *l* and the plate *y* which is attached to piston *l*. Springs *x* and *x*₁ are arranged to normally tend to retract unitary piston *i*—*l*₁ to starting position. The pressure liquid in the pressing cylinder *l* lifts up the valve *k* and passes through the opening in the piston *i*, through the tube conduit *g* and the opened pressing valve *e* into the water container at *u*.

In this position the expelled plate lies upon the lower stamp at the height of the press mould. The filling slide *a* is now moved over the press mould for the second filling operation. During this movement the driver *b*₁, *c*₁ pushes the expulsion valve *f* open. Water exhausts from the expulsion piston *s* which falls back into its original position by its own weight or is brought back into this position in known manner mechanically or hydraulically, the filling slide pushes the pressed plate away from the press table and at the same time places the material to be pressed as a repeat filling in the press mould. Whilst the filling slide *a* is being withdrawn the second pressing operation commences. A motion may be applied positively to the filling slide beneath the silo for the purpose of distributing the material uniformly in the filling slide.

What I claim is:

1. A hydraulic press comprising an upper piston and a lower piston, a filling slide for introducing a ceramic mass between said upper and lower pistons for compression therebetween into a pressed body, means controlled by the motion of said slide for supplying pressure water to said upper piston to cause it to move downwardly to compress said ceramic mass, a pressure accumulator, an exhaust conduit leading from said upper piston to said lower piston through said pressure accumulator, a pressure regulating non-return valve in said exhaust conduit intermediate said upper piston and said pressure accumulator, said valve being arranged to open when said upper piston has completed its downward motion so as to allow pressure water to pass to and lift up said lower piston whilst said pressed body is held fast between said upper and lower pistons.

2. A hydraulic press comprising an upper piston and a lower piston, a filling slide for introducing a ceramic mass between said upper and lower pistons for compression therebetween into a pressed body, a pressure water conduit for supplying pressure water to said upper piston to cause it to move downwardly to compress said ceramic mass, a valve in said pressure water conduit, a driver upon said slide, arranged to open and close said valve upon motion of said slide, a pressure accumulator, an exhaust conduit leading from said upper piston to said lower piston through said pressure accumulator, a pressure regulating non-return valve in said exhaust conduit intermediate said upper piston and said pressure accumulator, said valve being arranged to open when said upper piston has completed its downward motion so as to allow pressure water to pass to and lift up said lower piston whilst said pressed body is held fast between said upper and lower pistons, an exhaust valve connected to said exhaust conduit adjacent said

lower piston for exhausting water from said lower piston and to cause said lower piston to sink, and a second driver upon said slide arranged to open and close said exhaust valve upon motion of said slide.

3. A hydraulic press comprising a main upper piston and a lower piston, an auxiliary upper piston integral with said main upper piston, a filling slide for introducing a ceramic mass between said upper and lower pistons for compression therebetween into a pressed body, means controlled by the motion of said slide for supplying water to said auxiliary piston to cause it to move downwardly together with said main upper piston, a bore through said auxiliary upper piston, a valve in said bore arranged to open when said auxiliary piston has travelled a predetermined downward distance and to admit water through said bore to said main upper piston to cause it to move downwardly to compress said ceramic mass, a pressure accumulator, an exhaust conduit leading from said main upper piston to said lower piston through said pressure accumulator, a pressure regulating non-return valve in said exhaust conduit intermediate said main upper piston and said pressure accumulator, said valve being arranged to open with said main upper piston has completed its downward motion so as to allow pressure water to pass to and lift up said lower piston whilst said pressed body is held fast between said upper and lower pistons.

4. A hydraulic press comprising a main upper piston and a lower piston, an auxiliary upper piston integral with said main upper piston, a filling slide for introducing a ceramic mass between said upper and lower pistons for compression therebetween into a pressed body, a pressure water conduit for supplying pressure water to said auxiliary upper piston to cause it to move downwardly together with said main upper piston, a valve in said pressure water conduit, a driver upon said slide, arranged to open and close said valve upon motion of said slide, a bore through said auxiliary upper piston, a valve in said bore arranged to open when said auxiliary piston has travelled a predetermined downward distance and to admit water through said bore to said main upper piston to cause it to move downwardly to compress said ceramic mass, a pressure accumulator, an exhaust conduit leading from said main upper piston to said lower piston through said pressure accumulator, a pressure regulating non-return valve in said exhaust conduit intermediate said main upper piston and said pressure accumulator, said valve being arranged to open when said main upper piston has completed its downward motion so as to allow pressure water to pass to and lift up said lower piston whilst said pressed body is held fast between said upper and lower pistons, an exhaust valve connected to said exhaust conduit adjacent said lower piston for exhausting water from said lower piston and to cause said lower piston to sink, and a second driver upon said slide arranged to open and close said exhaust valve upon motion of said slide.

JOHANN PETER SPENGLER.
